UNITED STATES PATENT OFFICE

BERTRAND PARADISE, OF BROOKLYN, NEW YORK

APPARATUS FOR INKING ENDLESS RIBBONS

Application filed December 18, 1929. Serial No. 415,029.

This invention relates to apparatus for inking endless ribbons.

The principal object of this invention is to provide apparatus whereby the required ink surface may be easily applied to an endless typewriter ribbon.

Another object of this invention is to provide a device upon which the ribbon to be inked may be easily and readily applied for inking, and further, to permit easy removal therefrom.

Still other objects of this invention reside in the simplicity of instruction, the economy with which it may be produced and the high degree of efficiency derivable therefrom.

Numerous other objects of this invention will be readily apparent from an examination of the following specification taken in conjunction with the accompanying drawing, in which—

Figure 1 is a vertical sectional view taken on the line 1—1 of Figure 2 showing by dotted lines the ribbon-carrying spindles raised to inoperative position.

Figure 2 is a top plan view showing part of the structure cut away to illustrate the ball bearing assembly of the ribbon-carrying spindles.

Referring more specifically to the drawing, there is the base 10 upon which is placed a reservoir or container 11 which holds the ink 12 to be applied by my apparatus. An inking roller 13 is mounted on a shaft 14 so as to be rotatable therewith, within the reservoir 11, partially immersed in the ink 12. A suitable driving means, such for example a pulley 15 is mounted upon the shaft 14 so that rotary motion may be transmitted from some external source to the inking roller 13. Frictionally engaging the inking roller 13 is another and preferably smaller idle roller 16 in contact therewith for removing any surplus ink from the surface of the inking roller 13.

The roller 16, however, may be rotated by an external drive and means may be provided to bring the roller 16 into contact with the inking roller 13 so as to regulate the amount of ink carried up by the inking roller 13.

A standard 17 is mounted on the base 10 for supporting a lever 18 which is pivoted between its ends to the standard by a pin or other fulcruming device 19. Positioned at one end of this lever 18 are a pair of associated rotatably-mounted spindles 20 equipped with suitable anti-friction bearings 21. These spindles are spaced apart and are parallel to each other and project laterally from the lever. They are adapted to support an endless ribbon or ribbon material 22 from which endless ribbons are cut.

In operation, the ribbon is brought into contact with the inking roller between one of the spindles 20 and the inking roller 13.

To permit easy application or removal of the ribbon 22 to or from the spindles 20, the latter may be tapered as indicated at 23.

A gravity tension roller 24 is provided to maintain the required tension of the ribbon 22 and to prevent the ribbon 22 from slipping on the spindles while the device is in use. This tension roller 24 is preferably fluted as at 25 to give a minimum of contact with the ribbon. The tension roller 24 is rotatably mounted upon a shaft 26 at one end of a lever 27 which is pivoted to a bracket 28 on the lever 18 by a bolt 29.

To maintain the ribbon carrying portion of my apparatus raised normally to inoperative position, a contractile spring 30 or its equivalent is provided. This spring has one end 31 suitably fastened to the base 10 and the other end fastened as at 32 to a point intermediate the fulcrum 19 of the lever 18 and the free end thereof. It will, therefore, be apparent that the contractile spring normally urges the ribbon carrying portion away from the inking roller 13.

The standard 17 has an angularly projecting arm 33 provided at its upper end with a laterally projecting pin 34 located in the path of movement of the end 35 of the lever 27 and to cause this end of the lever to be depressed when the ribbon carrying portion of the lever 18 is raised by the action of the contractile spring 30. This depression of the end 35 of the lever 27 causes the tension roller 24 to be raised clear of the endless ribbon 22 so that the ribbon may be removed from the

spindles with facility and another ribbon applied.

The dotted lines indicate the spindles raised and out of contact with the inking roller 13 due to the action of the contractile spring 30 with the tension roller also raised as described above so that the ribbon 22 may be removable or another inserted. After the application of the ribbon 22 to the spindles, it is necessary to bring the ribbon 22 into contact with the inking roller 13 and for this purpose any suitable means may be used, as for example a flexible cord 36 passing over the pulley 37 and having its ends connected to the free end of the lever 18 and a treadle respectively.

In operation, the contractile spring 30 urges the free end of the lever 18 downward, thereby raising the ribbon carrying spindles 20. This, at the same time, causes the lever 27 to contact at 35 with the pin 34 raising the gravity tension roller 24. The endless ribbon 22 may then be applied to the spindles 20. A continuous rotary motion is imparted to the inking roller 13 from some external source through the pulley 15 and shaft 14, and as the inking roller rotates, ink is taken upon its surface from the supply 12 in the reservoir 11. Roller 16 in frictional engagement with the inking roller 13 is rotated, thereby causing any surplus ink to be removed. The ribbon is brought into contact with the inking roll 13 by moving the flexible cord 36 in the direction indicated in the drawing by the arrow. When the ribbon carrying spindles 20 are lowered, the lever 27 is correspondingly lowered from contact with the pin 34 and the fluted tension roller 24 is permitted to rest upon the ribbon 22. The weight of the tension roller 24 maintains the required tension upon the ribbon 22 and prevents its accidental slipping on the spindles 20 while the ribbon is being inked. The ribbon 22 is brought into contact with the inking roller 13 between one of the spindles and the inking roller. This permits the application of any degree of pressure in bringing the ribbon 22 into contact with the inking roller 13 without causing any sagging or stretching of the ribbon 22. As a positive frictional contact is thereby made, the rotary motion of the inking roller 13 is transmitted to the endless ribbon 22 causing it to move relatively with the inking roller 13. This results in having the required amount of ink applied evenly to the entire surface of the ribbon 22.

In using the term "ribbon" it is to be understood that I use the same in the broadest possible sense to include any endless band or material to be inked.

While I have specifically described the structure and operation of the form of my invention shown in the drawings, it will be understood that my invention is not confined to the specific details shown and described, as

numerous changes and modifications and the full use of equivalents, may be resorted to without departing from the spirit or scope of the appended claims.

What is claimed is:

1. A device for inking endless ribbons including a rotatably mounted inking roller, a plurality of associated rotatably mounted spindles for carrying an endless ribbon, means for moving said spindles with respect to said inking roller, said means including a pivoted lever and an operating spring therefor, and means for applying tension to the endless ribbon, said tensioning means consisting of a lever, a roller carried thereby, and means for engaging the free end of said latter lever for depressing the same and moving said roller from the ribbon.

2. In an inking mechanism, the combination with an ink-supply device, of a movable member normally spaced from said ink-supply device, and means on said member for movably supporting a ribbon to be inked including tensioning means, said tensioning means comprising a fluted roller and means for moving said fluted tensioning roller to an inactive position.

3. In an inking mechanism, the combination with an ink-supply device of a support, a member pivoted to said support and movable toward or away from the said ink-supply device, means on said member for movably supporting a ribbon to be inked including tensioning means, said tensioning means comprising a lever pivoted intermediate its ends to said member and a gravity tension roller carried by one end of said lever, and means engageable with the free end of said lever so constructed and arranged that upon movement of the member away from said ink-supply device the lever will be depressed and the tension roller moved from the ribbon.

Signed at Brooklyn in the county of Kings and State of New York this 12th day of December, A. D. nineteen hundred twenty-nine.
